(57) **CLAIM**

The ornamental design for a wireless communications assembly, as shown and described.

DESCRIPTION

FIG. 1 is a front, top perspective view of a wireless communications assembly showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The wireless communications assembly is shown with a symbolic break in its length. The appearance of any portion of the article between the break lines forms no part of the claimed design.

The broken lines show portions of the wireless communications assembly that form no part of the claimed design.
